UNITED STATES PATENT OFFICE.

CHARLES H. FISH, OF RYE, NEW HAMPSHIRE.

CRANK ARM.

Application filed April 7, 1921. Serial No. 459,340.

To all whom it may concern:

Be it known that I, CHARLES H. FISH, a citizen of the United States, residing at Rye, in the county of Rockingham and State of New Hampshire, have invented certain new and useful Improvements in a Crank Arm, of which the following is a specification.

This invention relates to crank arms, and is particularly concerned with crank arms intended to oscillate the lay of a loom.

It is the chief object of the invention to devise a crank arm construction which can be manufactured economically, which will be light in weight, which will have substantially greater length of life than the crank arms commonly used, which will eliminate the difficulties experienced in prior constructions in properly lubricating the bearing surfaces, and in which the wearing parts can be economically renewed.

The nature of the invention will be readily understood from the following description when read in connection with the accompanying drawings, and the novel features will be particularly pointed out in the appended claims.

Referring now to the drawings,

Figure 1 is a side elevation of a crank construction embodying the invention;

Fig. 2 is an edge view of the construction shown in Fig. 1;

Fig. 3 is a side elevation of a modified construction; and

Fig. 4 is a cross sectional view on the line 4—4, Fig. 3.

Referring first to Figs. 1 and 2, the construction there shown comprises an arm 2, preferably, although not necessarily, made of wood, this arm having a V-shaped groove 3 cut in the left-hand end thereof, and also having flat shoulders 4—4 at the opposite sides of said groove. For convenience in sawing this groove a hole 5 preferably is bored through the arm at the apex of the groove and the sawing or cutting operations are then performed.

Seated in the groove 3 is a bearing block 6 which may be either of the solid or split type, the latter type being shown, this block having a hole 7 formed therethrough to receive a crank pin, wrist pin, or the like. The block is held on the end of the arm 2 by a strap 8 of approximately U-shape which fits over the end of the bearing block and extends back along opposite sides of the arm 2 where it is secured to the arm by two bolts

9 and 10. The bolt 10 extends simply through the strap 8 and arm 2, but the bolt 9 is located in a hole, the axis of which lies substantially in the plane of the shoulders 4—4. That is, this hole is formed partly in the end surface of the arm 2 and partly in the lower portion of the bearing block 6. It will be observed that the groove 3 extends in a direction parallel to the axis of the bearing surface 7, and this interlocking relationship of the bearing block and the arm 2 prevents relative lateral movement between these parts in a direction at right angles to said axis, while the bolt 9 prevents relative lateral movement between these parts in a direction parallel to said axis. This construction therefore secures the block firmly to the end of the crank arm.

While the bearing block 6 may be made of any suitable material, I prefer to make it of wood which has been treated in some manner to render it self-lubricating, and I have found that remarkably good results are obtained by making this block of the material known commercially as "cellugraph." This material consists of hard wood chemically treated to make it self-lubricating and it has a very low co-efficient of friction, exceptionally long life, and is relatively economical.

The construction illustrated at the right-hand end of the crank arm 2 is the same as that just described except that the parts are slightly smaller and the bearing block is of the solid type instead of being split.

It will now be appreciated that this crank is relatively light in weight but is very sturdy and substantial in construction. Due to the peculiar nature of the design and the materials used it can be manufactured very economically and it has been demonstrated in actual practice that it has a remarkably long life even under severe conditions of service. When a loom is stopped suddenly the longitudinal thrust on the crank arm is very severe and it will be observed that the construction shown is well adapted to withstand this thrust since the block 6 is seated on the shoulders 4—4 and also on the bolt 8. The V-shape construction of the groove and the extension from the block that is seated in it of course exert a certain tendency to split the arm, but this tendency is effectively resisted by the bolts 9 and 10 which squeeze the legs of the strap 8 against the opposite sides of the arm 2.

The grain of the wood in the arm 2 should

run longitudinally of the arm and I prefer also to have the grain of the wood in the bearing block 6 run in this direction so that the thrust exerted on or by the wrist pin 5 or crank pin will come on the end of the grain of the wood which withstands both deformation and wear more effectually than does the side of the grain. This arrangement, however, is not essential.

10 The construction shown in Figs. 3 and 4 comprises a crank arm 12 having a square shouldered groove 13 formed therethrough with flat shoulders 14—14 at opposite sides of this groove, and a bearing block 15 shaped 15 to fit both the groove 13 and the shoulders 14. A strap 16 extends around the end of the bearing block and is secured to the crank arm by a bolt 17. This bearing block has a hole 18 formed therethrough to receive 20 a wrist pin or crank pin.

In this construction the groove 13 and the bolt 17 perform substantially the same functions that are performed by the groove 3 and bolt 10 in the construction above described. That is, they prevent relative lateral movement between the bearing block and crank arm in one direction and also prevent relative longitudinal movement of these parts. In order to hold the parts 25 against relative lateral movement in the groove 13 the strap 16 preferably is made of channel cross section, as clearly shown in Fig. 4, so that it embraces the opposite sides of the parts 12 and 15 and thus prevents any lateral movement between these parts in a direction parallel to the axis of the bearing surface 18.

The construction at the opposite or right-hand end of the crank shown in Fig. 3 is 40 the same as that just described except for minor differences in the shape of the parts. This construction has the same general advantages as those above mentioned in describing the form of the invention shown 45 in Figs. 1 and 2. It should be noted that the bearing blocks can be very easily replaced whenever they become worn to such an extent that this is necessary, and since these parts can be manufactured very economically this replacement can be made at 50 a trifling expense.

An especially important advantage of the construction above described is that the bearing members are self-lubricating. I 55 find that by using bearing blocks made of "cellugraph" a crank construction is obtained which is not only the equal in every respect of those heretofore used but is actually superior both in serviceability and in 60 economy. The necessity for lubricating the bearing surfaces of crank arms of the character heretofore used has made these constructions very objectionable for loom work because of the liability to spot the yarn or 65 goods with the lubricant used. Since my

construction avoids the necessity for lubricating material, it eliminates not only this danger of damaging the goods being woven, but also the labor necessary to apply the lubricant properly and the expense for the 70 lubricant itself.

While I have herein described the forms of my invention which I consider at present to be preferable, it will be readily appreciated that these embodiments of the invention may be modified in minor particulars without departing from the spirit or scope of the invention.

Having thus described my invention what I desire to claim as new is:

1. A device of the character described comprising, in combination, a crank arm grooved at one end, a bearing block seated in said groove, a strap fitting around the outer end of said block, and means for securing said strap to said arm whereby said strap secures said block in said groove.

2. A device of the character described comprising, in combination, a crank arm grooved at one end, a self-lubricating bearing block seated in said groove, a strap fitting around the outer end of said block, and a bolt securing said strap to said arm at opposite sides thereof.

3. A device of the character described comprising, in combination, a crank arm, a self-lubricating bearing block having an interlocking engagement with one end of said arm preventing relative lateral movement between said arm and block in one direction, and means for securing said block to said arm, said securing means preventing relative lateral movement between said block and arm at right angles to said direction and also preventing movement of the block 100 longitudinally away from the arm.

4. A device of the character described comprising, in combination, a crank arm, a wooden bearing block secured to one end of said arm and having a bearing surface 110 formed therein, said end of the arm being grooved in a direction parallel to the axis of said bearing surface and having flat shoulders at opposite sides of said groove, said block having parts to fit said groove 115 and shoulders, a strap fitting over one end of said block and extending along said arm at opposite sides thereof, and a bolt extending through said arm and strap and operative to secure said parts together and tending to squeeze said shoulders toward each other.

5. A device of the character described comprising, in combination, a wooden crank arm having a V-shaped groove in one end thereof, a self-lubricating wooden bearing block seated in said groove, a strap fitting around the outer end of said block, and means securing said strap to said arm at opposite sides thereof.

6. A device of the character described comprising, in combination, a crank arm, a self-lubricating wooden bearing block mounted on one end of said arm, a strap 5 fitting around the outer end of said block and extending backwardly along said arm at opposite sides thereof, and means for securing said strap to said arm, said strap having a channel therein to receive said bearing 10 block.
7. A device of the character described comprising, in combination, a crank arm having a groove in one end thereof with shoulders at opposite sides of said groove, 15 a bearing block seated in said groove, a strap fitting around the outer end of said block and extending backwardly along said arm at opposite sides thereof, and two bolts securing said strap to said arm, one of said
- bolts having its axis located substantially in 20 the plane of said shoulders.
8. A device of the character described comprising, in combination, a crank arm grooved at one end, a bearing block seated 25 in said groove, a strap fitting around the outer end of said block, and means for securing said strap to said arm, said strap and block having interengaging parts preventing movement of the block endwise of 30 said groove.
9. A device of the character described comprising, in combination, a crank arm, a self-lubricating bearing block having interlocking connection with one end of said arm, a strap fitting around the outer end 35 of said block, and means for securing the end portions of said strap to said arm.

CHARLES H. FISH.
